HAMMOCK-SUPPORT.

1,217,963.

Specification of Letters Patent.

Patented Mar. 6, 1917.

Application filed February 3, 1916. Serial No. 75,965.

To all whom it may concern:

Be it known that I, SELBY A. LAING, a citizen of the United States of America, and resident of Moundsville, county of Marshall, 5 and State of West Virginia, have invented certain new and useful Improvements in Hammock-Supports, of which the following is a specification.

This invention relates broadly to hammock supports for beds, and more particularly to a sling for a child's hammock.

The primary object of the invention is to provide a simple and inexpensive support which is designed to be removably mounted 15 upon any ordinary bed for supporting a child's hammock in a position above and transversely of such bed.

A further object of the invention is to provide a device of the character mentioned 20 which is adjustable in height and which may be quickly and conveniently mounted and dismounted.

With these and other objects in view, the invention resides in the features of construction, arrangement of parts and combinations of elements which will hereinafter be 25 fully described, reference being had to the accompanying drawings, in which—

Figure 1 is a front elevation of the invention applied to a bed;

Fig. 2 is a similar view of the hammock and the upper ends of the adjustable supports, showing a brace-rod interposed between the latter;

Fig. 3 is a side elevation of one of the supports; and—

Fig. 4 is an enlarged detail view illustrating a brace-connecting means.

Referring to said drawings, in which like 40 designating characters distinguish like parts throughout the several views—

1 indicates the side-rails of an ordinary bed, which rails may be of any of the various forms commonly used in beds; and 2 indicates the side-members of the frame of a common type of bed-spring, which frame may be of any of the various common forms wherein the side-members are exposed.

Mounted upon the opposite sides of the 50 bed are two precisely similar upright supports for a hammock, each support being designed to have an end of a hammock, as 3, attached to its upper end. Each support comprises a vertically disposed body member 4, preferably of tubular form, having adjustably mounted at its lower end a yoke

6 which is designed to seat upon the side-rail 1 of a bed with the parallel members thereof disposed in straddling relation to said side-rail. In the embodiment herein shown a 60 stem 5 carried by said yoke is adjustable within the lower end of the tube 4. A set-screw 7 carried by said tube 4 is designed to be set in impinging relation to the stem 5 for holding the latter in adjusted position. 65 Telescoped within the upper end of said tube 4 is a rod 8 having a ring or hook 9 at its upper end for receiving an end of the hammock 3. A set-screw 10 carried by said tube 4 is designed to be set in impinging relation 70 to said rod 8 for holding the latter in adjusted position.

A brace 11 is provided whereby the support is braced in upright position both against inward swinging and lateral swinging movements. Said brace comprises a metal strap which is bent into substantially U-shape in side elevation and which is attached to the side of the tube 4 intermediate the ends of the latter. The lateral members 80 11^a of said brace have their end portions bent to form inwardly directed arms 12 which are designed to closely underlie the side-rail 1 of the bed and which have curved terminals 13 designed to extend upward between said side-rail and the adjacent side-member 2 of the spring-frame and to overlie the latter, as is clearly shown in Fig. 1.

A transversely disposed bar 14 has its opposite ends rigidly attached to the substantially vertical lateral members 11^a of the brace 11, and a bolt 15 directed inward through the middle portion of said bar is movable within vertical slots 16 provided in directly opposite sides of the tube 4, said bolt being projected through said slots and having a nut 17 threaded on its inner end for preventing withdrawal. The bar 14 is preferably located about midway between the lower ends of the lateral members 11^a 100 of the strap and the transverse upper portion 11^b of said strap, which latter has a vertical slot 18 therein which opens outward through the upper edge thereof, as shown in Figs. 3 and 4. Said slot 18 is adapted, 105 when the strap-like brace is in adjusted position, to receive therein a bolt 19 carried by the tube 4. A wing-nut 20 is threaded upon the outer end of said bolt 19 and is adapted to be set in frictional engagement with the 110 upper portion 11^b for holding the brace in adjusted position.

As is obvious, the hammock 3 mounted upon the opposite supports will serve to maintain the latter against outward swinging movement with respect to the bed, as shown in Fig. 1. However, for rigidly maintaining said supports against such movements, a transverse rod may be connected at its ends to the upper ends of the supports, as shown in Fig. 2. Said rod is preferably 10 of a telescopic type, adapting it for use on various widths of beds, and preferably consists of a central tubular member 21 and oppositely disposed rod sections 22, the latter having their inner ends adjustably received within the ends of said tubular member and their outer ends detachably secured to the upper ends of the rods 8. Said tubular member 21 preferably has a ring or eye 23 formed thereon to which may be attached 15 the ends of straps or cords 24 having their opposite ends attached at suitable points to the hammock for maintaining the latter against tipping over.

In applying the supports to a bed, the 25 wing nut 20 being loosened to permit the brace 11 to drop to the extent permitted by the slots 16, the arms 12 of said brace are placed in closely underlying engagement with the side-rail 1 of the bed with their 30 terminals 13 overlying the side-member 2 of the spring frame. Supporting said brace in this position by hand, the yoke 6 is placed in seated position upon said side-rail, the set-screw 7 having been first released or loosened 35 to permit said yoke to be adjusted. When said yoke has been properly adjusted, said set-screw 7 is tightened, as is also the wing nut 20, the tube 4 having been lowered to a point where the bolt 19 seats in the slot 18 40 in the transverse member of the brace. The rod 8 is then adjusted to a proper height, whereupon the device is ready for receiving thereon an end of the hammock 3.

What is claimed is—

45 1. A sling for a child's hammock, comprising a pair of upright supports designed for mounting upon opposite sides of a bed, each support comprising an upright body member, a yoke carried by the lower end of said member and designed to seat upon the side-rail of the bed, a brace mounted upon and vertically adjustable with respect to said member, means for maintaining said brace in adjusted position, and arms carried by 50 said brace having portions for seating in underlying relation to said side-rails and having terminal portions for overlying the side member of a spring frame.

55 2. A sling for a child's hammock, comprising

ing a pair of upright supports designed for 60 mounting upon opposite sides of a bed, each support comprising an upright body member, means carried by said member for seating upon the side-rail of the bed, and a brace adjustably connected to said member having 65 portions designed to underlie said side-rail and to overlie the side member of a spring frame.

3. A sling for a child's hammock, comprising a pair of upright supports designed for 70 mounting upon opposite sides of a bed, each support comprising an upright body member, a yoke adjustably mounted on said member and adapted to seat upon a side-rail of the bed, and a brace carried by said member, 75 said brace having a substantially vertical member located at each side of said body member, each vertical member being bent inward to form a portion for underlying said side-rail and a terminal portion for 80 overlying the side member of a spring frame.

4. A sling for a child's hammock, comprising a pair of upright supports designed for 85 mounting upon opposite sides of a bed, each support comprising an upright body member, a yoke adjustably mounted on said member and adapted to seat upon a side-rail of the bed, a brace carried by said member, said 90 brace having a substantially vertical member located at each side of said body member, each vertical member being bent inward to form a portion for underlying said side-rail and a terminal portion for overlying the side member of a spring frame, said brace 95 being vertically movable with respect to said body member, and means for holding said brace in adjusted position.

5. A sling for a child's hammock, comprising a pair of upright supports designed for 100 mounting upon opposite sides of a bed, each support comprising an upright tubular member, a yoke for seating upon a side-rail of the bed, said yoke having a stem adjustably received within said tube, and a substantially 105 U-shaped brace adjustably mounted on said tube, the substantially parallel members of said brace being disposed at opposite sides of said tube and having their lower ends bent to form portions for underlying said 110 side-rails and adjacent portions for overlying the side-member of a spring frame.

In testimony whereof, I affix my signature in presence of two subscribing witnesses.

SELBY A. LAING.
